UNITED STATES PATENT OFFICE

CHARLES S. THOMPSON, OF PARK RIDGE, AND WILLIAM B. LONG, OF CHICAGO, ILLINOIS, ASSIGNORS TO UNION SPECIAL MACHINE COMPANY, OF CHICAGO, ILLINOIS, A CORPORATION OF ILLINOIS

FILLED-BAG-CLOSING MACHINE

Application filed May 16, 1922. Serial No. 561,523.

The invention relates to new and useful improvements in filled bag closing machines, and more particularly to a filled bag closing machine having a conveyor on which the 5 filled bag rests and is moved during the closing of the same and a stitching mechanism which overhangs the conveyor.

An object of the invention is to provide a filled bag closing machine of the above type, 10 wherein both the conveying mechanism and the stitching mechanism are capable of vertical adjustment, and means is provided for vertically adjusting the conveying mechanism and stitching mechanism independently of 15 each other or simultaneously toward and from each other.

A further object of the invention is to provide a filled bag closing machine, wherein the sewing head is capable of vertical adjustment and wherein said sewing head is driven by a motor which moves vertically with the 20 sewing head.

A still further object of the invention is to provide a filled bag sewing machine wherein 25 the sewing head is capable of vertical adjustment and wherein the sewing head is controlled by a treadle, and the controlling means includes devices which automatically compensate for the different positions of the 30 sewing head.

Another object of the invention is to provide a filled bag sewing machine wherein the carriage carrying the filled bag and presenting the same to the stitching mechanism is 35 moved by hand along tracks disposed substantially horizontally, which tracks are capable of being adjusted vertically relative to the sewing head for positioning the carriage for different size bags.

Another object of the invention is to provide a filled bag sewing machine having a traveling carriage with a stop mechanism for normally holding said carriage in position 45 where the bag may be placed thereon prior to the presenting of the same to the stitching mechanism and wherein said stop mechanism is automatically released when the bag is placed on the carriage.

These and other objects will in part be

obvious and will in part be hereinafter more fully disclosed.

In the drawings which show by way of illustration one embodiment of the invention—

Figure 1 is a side view of a machine embodying the improvements;

Fig. 2 is a front view of the same;

Fig. 3 is a sectional view on the line 3—3 of Fig. 1;

Fig. 4 is a top plan view of the upper portion of the machine;

Fig. 5 is a sectional view on the line 5—5 of Fig. 4;

Fig. 6 is a view showing in section the means for raising and lowering the sewing head and conveying carriage, a portion of the column for supporting the parts and in side view the compensating means forming a part of the controlling mechanism for the sewing head;

Fig. 7 is a view partly in section, showing the stop mechanism for the carriage;

Fig. 8 is an enlarged view showing the compensating mechanism forming a part of 75 the controlling mechanism when disengaged from the treadle;

Fig. 9 is a view partly in side elevation and partly in section showing carriage and supporting tracks therefor.

The invention is applied to a filled bag sewing machine of the type wherein the filled bag is placed on a carriage capable of traveling back and forth on tracks. These tracks are mounted on a supporting frame so that they 85 may be adjusted vertically. The sewing head is also mounted on the same supporting frame so as to overhang the traveling carriage and said sewing head is also capable of being adjusted vertically. The same bracket which supports the sewing head also supports the motor for driving the sewing head. A vertical screw shaft is provided for adjusting the sewing head vertically on the frame and for supporting the same in adjusted positions. Another vertical screw shaft is provided for adjusting the tracks and carriage vertically on the supporting frame and said screw shaft operates to hold the tracks in the position to which they are adjusted. 95 100

Means is provided whereby the screw shafts may be independently rotated or simultaneously rotated. This enables the sewing head and the traveling carriage to be quickly moved toward or from a given point simultaneously or the operator may move the sewing head independently of the supporting carriage and, again, the operator may move the supporting carriage independently of the sewing head. This enables the machine to be readily adapted for operating upon bags of various sizes and at the same time maintain the stitching level so that it will be very convenient to the operator.

As noted above, the sewing head and the operating motor are shiftable together vertically. The stitching mechanism is controlled by a lever which is also mounted to move bodily with the sewing head. The distance of this lever from the floor will, therefore, vary as the sewing head is shifted. A treadle is mounted on the supporting base of the machine, whereby the sewing head is controlled and in order to take care of the varying heights to which the sewing head may be placed, automatic means has been provided forming a part of the controlling means which automatically compensates for the different heights to which the sewing head may be set. This compensating means consists broadly of a rotatable part having a flexible connection with the controlling lever of the sewing head. A weight is also attached to this rotatable part by a flexible supporting means and the weight normally tends to rotate the part so as to wind up the flexible connection extending to the controlling lever of the sewing head. This weight when the rotatable member is free will take all the slack out of the flexible connection to the controlling lever. A treadle is connected to an operating lever which when depressed will clutch up with the rotatable part and positively turn the rotatable part so as to actuate the controlling lever.

The invention will possibly be better understood by a more detail description of the apparatus shown in the drawings which illustrate one embodiment of the invention.

In the drawings, the machine is shown as consisting of a supporting base 1, centrally of which is a vertical column 2. This vertical column may be formed of a hollow cylindrical pipe which is of sufficient strength to support the parts and yet not of excessive weight. Extending out from the supporting base 1 are four substantially horizontally disposed legs 3, each of which is provided with a castor or supporting roller 4 which is connected to the leg so that said castor or roller may readily turn to accommodate the direction in which the apparatus is to be moved. Extending from two of the legs are bolts 5 which may be adjusted vertically and secured in adjusted position by

means of a lock nut 6. These bolts may be used to level the machine and securely hold the machine from movement when it is brought to a desired position for use. The legs 3 are made of angle iron and these angle iron sections are bolted to the supporting base 1. Brace rods 7 are also bolted to the vertical portions of the angle irons forming the legs and this makes up a skeleton supporting portion for the apparatus which is strong and durable; also which is light and which can be very cheaply made.

At the upper end of the column 2 there is an adjustable bracket 8. Said bracket is formed in part by a sleeve 9 which slides freely on the column 2. Said sleeve has formed integral therewith a forwardly projecting support 10. The sewing head is indicated at 11. Said sewing head is bolted to a plate 12 formed as a part of the support 10. The sewing head is of the usual construction. Said sewing head has a needle bar 13 carrying a needle 14 and the needle bar is reciprocated by means of a needle lever 15, which needle lever is in turn oscillated by an eccentric strap 16, co-operating with an eccentric on the main shaft 17. The machine also includes a suitable presser foot 18, and feed dog 19 which is actuated in the usual manner from the main shaft for intermittently feeding the mouth of the bag step by step to the stitching mechanism as it is stitched. There is also mounted in the cylindrical arm 20, besides the feeding mechanism, complementary stitch forming mechanism which co-operates with the needle in forming the stitches. This sewing head may be of any desired construction and further description thereof is not thought necessary.

Also, extending laterally from the sleeve 9 is a second supporting member 21. This supporting member 21 is on the opposite side of the sleeve from the supporting member 10. A motor 22 for operating the sewing head is secured to a plate 23 which is bolted by means of bolts 24 to the support 21. The motor is secured to this plate 23 by bolts 25—25. It will be noted that the motor is on the opposite side of the column from the sewing head and therefore in a sense counter-balances the tendency of the weight of the sewing head to cause the sleeve to bind on the column so that the sleeve will more smoothly move up and down on the column. The plate 23 may be adapted to different sizes and styles of motors.

Also extending out from the sleeve 9 is a support 26 in which is mounted a transmitter for transmitting power from the motor to the sewing head. This support 26 consists of an upper arm 26^a and a lower arm 26^b. Journaled in these arms is a shaft 27. Mounted on the upper end of the said shaft 27 is a groove pulley 28. The groove pulley 28 is adapted to be belted by means of a belt 29 to a belt 125 130

wheel 30, on the main shaft 17 of the sewing head. Also fixed to the shaft 27 is a combined clutch and brake disk 31. On the under face of said disk 31 there is a flexible facing 32 which is adapted to be engaged by means of a belt wheel 33 which is free on the shaft and capable of endwise movement on the shaft. This belt wheel 33 is connected by means of a belt 34 to a belt wheel 35 on the motor shaft so that when the motor is running the belt wheel 33 is continuously operated. A spring 36 normally presses the belt wheel 33 away from the facing 32 of the disk 31, so that these parts are disengaged and while disengaged the loose belt wheel 33 will run freely without in any way turning the shaft 27.

As a means for bringing the loose belt wheel into driving contact with the disk 31, a controlling lever 37 has been provided. This controlling lever 37 is pivotally supported by the bracket 8 so as to swing in a vertical plane and said lever carries a forked arm 38 which straddles the shaft 27 and is adapted to move the belt wheel 33 endwise on the shaft. A ball bearing 39 is located between the end of the forked arm 38 and the belt wheel 33. There is also a ball bearing 40 between the disk 31 and the upper bracket arm 26. This controlling lever at its free end is connected to a flexible member 41 which is capable of being depressed by means of a treadle which will be described later, and when depressed the belt wheel 33 makes contact with the disk 31, rotates the shaft 27 and this in turn rotates the main shaft of the sewing head. When the flexible member 41 is released, then the controlling lever is moved by means of a spring so as to lower the forked arm 38 and this permits the spring 36 to separate the driving wheel 33 from the disk 31. Said spring 36 bears against a washer 42 which in turn bears against the belt wheel 33. Of course, gravity also tends to move the belt wheel 33 downwardly out of engagement with the disk 31.

The shaft 27 is a hollow shaft and is provided with a suitable oil supplying means, indicated at 43. The controlling lever 37 is provided with an upper arm 44, which is moved forward into contact with the cylindrical surface of the disk 31 when said controlling lever is swung to release the belt wheel 33. This arm 44 serves as a brake to stop the rotation of the transmitter and thus stop the rotation of the sewing mechanism.

Also extending laterally from the sleeve 9 is an arm 45 in which is fixedly mounted a nut 46 adapted to engage a threaded shaft 47. As this threaded shaft is rotated the nut 46 will be caused to travel one way or the other on the shaft for the reason that the shaft is mounted in suitable bearings which prevent any endwise movement thereof. Said shaft 47 at its upper end is mounted in a bearing carried by a laterally projecting arm 48 se-

cured to the upper end of the column. The shaft is provided with a reduced section 49 at its lower end which is mounted in a bracket 50 secured to the column intermediate its ends. A ball bearing 51 engages a shoulder on the shaft and thus carries the weight of the sewing head and motor which are supported by the shaft. 70

It will be readily seen that when the shaft is rotated the sewing head will be raised or lowered depending upon the direction in which the shaft is rotated. 75

Splined on the lower end of the shaft is a beveled gear 52. This beveled gear is capable of being moved endwise on the shaft, 80 but any rotation imparted to the beveled gear will rotate the shaft. Extending laterally from the bracket 50 is a supporting arm 53, provided with a sleeve bearing in which is journaled a shaft 55. Rigidly secured to the outer end of the shaft 55 is a hand wheel 56 carrying a hand crank 57. This enables the shaft 55 to be rotated by hand. Fixed to the shaft 55 is a beveled gear 58 which is so positioned that the beveled gear 52 may mesh therewith when at one position on the shaft 47. There is a spring 59 between the beveled gear 52 and the bracket 50 which normally forces the gear 52 upwardly on the shaft 47 to which it is splined and to a point 90

where the teeth of the beveled gear 52 are out of mesh with the teeth of the beveled gear 58. Directly above the beveled gear 52 is a collar 60 which is provided with a radially projecting pin 61 which enables the collar to be freely turned. This collar is provided with a cam groove 62 (see Fig. 2). Fixed to the shaft 47 is a pin 63. When the collar is in the position shown in Fig. 6, this pin rides on the outer face of the collar and will cause the collar to force the beveled gear 52 downwardly compressing the spring 59 and bringing said beveled gear into mesh with the beveled gear 58 on the shaft 55. When, however, this collar 60 is turned so 100 that the pin 63 may move into the cam groove 62 then the collar will slide endwise on the shaft and permit the spring to force the beveled gear 52 out of mesh with the gear 58. 105

When the two gears above described are in mesh, then the sewing head may be raised and lowered by the turning of the shaft 55 through the aid of the hand wheel. If, however, these gears are out of mesh the turning of the hand wheel will not turn the shaft 47 and therefore said hand wheel may be turned without imparting any movements up and down to the sewing head. When the gear 52 is out of engagement with the gear 58 the sewing head will be supported in the position to which it has been adjusted for the reason that the pitch of the thread on the shaft 47 is very fine and the weight of the sewing head and motor is not sufficient to turn the shaft. 125

The filled bag which is to be closed is placed 130

on a carriage 64. This carriage 64 is mounted so as to be moved on supporting tracks 65—65. The tracks 65—65 are in turn mounted on arms 66—66, which arms are bolted to the opposite ends of a bracket 67, which bracket at the central portion thereof is provided with a sleeve 68 which is adapted to engage and freely slide vertically on the column 2. The bracket extends outwardly and downwardly from the sleeve and carries at its outer ends the arms 66, as above noted. The arms 66 are formed of angle irons and the tracks 65—65 are formed of the usual well-known U-bars or channel bars. These tracks are spaced the proper distance apart to receive the carriage. The carriage is provided with depending spaced brackets 69 arranged at each end thereof, and in these spaced brackets is a supporting shaft 70, and at each end of the shaft is a roller 71 mounted on ball bearings and these rollers are in the form of flanged wheels, as clearly shown in the drawings. The flanged wheels supporting the carriage run on the lower members of the U-bars forming the tracks 65—65 so that these U-bars serve as a housing for the wheels. This is quite an important feature for the reason that these filled bags are used in mills where there is a great deal of dust and dirt and the track serves as a housing for the wheels and thus in a measure protects the same from the dust and dirt. The tracks 65—65 are arranged substantially horizontally.

The bag to be stitched is placed on the carriage and the carriage is moved by the feed of the machine as the bag is being stitched and thus the bag is kept substantially vertical as it moves beneath the sewing head. It will be noted from Fig. 3 that the supporting plate of the carriage is slightly narrow at its forward end so as not to overlap the track 65. At the extreme left-hand end of the tracks there is a U-shaped rod 72 which is rigidly secured to the tracks. The ends of the rods extend down through the channel bars and are threaded. Nuts 73 and 74 above and below the channel bars rigidly and adjustably support the same. The forward end of the carriage passes between the vertical portion of the U-shaped rod 72 and causes the bag mounted on the carriage to engage said rods. Said rod will be adjusted so as to engage the bag at a point below its center of weight and as a result the bag will tilt forward over the rod and off from the carriage. As the bag tilts off from the carriage, by this engagement with the rod and swinging over the rod, the bottom of the bag will give the carriage a backward kick and this will cause the carriage to run back to the other end of the track.

As a means for holding the carriage at the right-hand end of the tracks until it is desired to move the same forward with a filled bag thereon, a stop mechanism has been

provided consisting of a lever 75. Said lever 75 is pivotally supported by a bracket 76 at the rear end of the lever and the forward end of the lever is capable of moving up and down in a second member 77 rigidly secured to the carriage. A spring 78 mounted in the member 77 bears against the under surface of the lever 75 and normally tends to raise the same. The lever is provided with an upwardly projecting portion 79 which is adapted to move up through a slot in the supporting plate of the carriage. It will readily be seen that when a filled bag is placed on the carriage it will engage this portion 79 of the lever and force it down; and, on the other hand, when the bag is removed from the carriage the spring 78 will raise the lever.

The upper member of the U-bars is provided with a notch 80 and this notch is so positioned that when the carriage is at the extreme right-hand end of the tracks, as viewed in Fig. 7, the lever will move up into the notch and hold the carriage in this position. Therefore, when the bag falls off the carriage and the carriage is given a kick backward, it will run to the other end of the track and the stop lever will be moved up into the notch not only stopping the carriage but holding it in this position ready to receive the next filled bag and until the filled bag is placed thereon.

The carriage is raised and lowered vertically to accommodate different sizes of bags by means of a threaded shaft 81. This shaft 81 is mounted in a step-bearing 82 at the lower end thereof and is provided with a reduced portion 83 at its upper end which is mounted in the bracket 50. A nut 84 is rigidly connected with the sleeve 68 and this nut engages the threaded shaft 81. When the threaded shaft 81 is turned the nut will travel endwise on the shaft and thus raise or lower the tracks supporting the carriage—depending upon in which direction the shaft is rotated.

At the upper end of the shaft 81 there is a beveled gear 85 which is adapted to mesh with the gear 58 when it is in the position shown in Fig. 6. This gear is normally forced in a downward direction on the shaft by a spring 86. The gear 85 is splined to the shaft and is free to move endwise thereof. A collar 87 mounted on the shaft limits the downward movement of the gear 85. A pin 88 on the shaft is adapted to co-operate with the cam groove 89 in the collar 87. A pin 90 is fixed to the collar 87 and serves as a means for rotating the collar. It will readily be seen that when the collar is in the position shown in Fig. 6, then the beveled gear 85 will be held in mesh with the beveled gear 58. When, however, the collar 87 is turned to the position shown in Fig. 2, then the beveled gear 85 is forced out of mesh with the beveled gear 58. When the beveled gear 85 is out of mesh with the beveled gear 58 then the hand

shaft may be turned without rotating the threaded shaft 81 and the threaded shaft 81 will support the tracks in the position to which they have been adjusted by reason of the fact that the thread on the shaft is of relatively fine pitch. It will thus be seen that the operator may by shifting the collars 60 and 87 either set the mechanism so that the sewing head and the carriage may be simultaneously adjusted or the sewing head may be adjusted without moving the carriage, and, again, the carriage may be adjusted without moving the sewing head. When the sewing head and carriage are simultaneously adjusted they will be simultaneously moved toward each other or from each other by reason of the fact that the shafts 47 and 81 when both in mesh with the gear 58 will be rotated in opposite directions.

20 The flexible member 41 which is connected with the controlling lever for the sewing head is connected at its lower end to a rotatable member 91. Said rotatable member is provided with two spaced grooves 92 and 93 and 25 the outer side walls of the grooves are chamfered or beveled outwardly away from the grooves. The flexible member 41 which is either in the form of a chain or cord is wound about the central portion of the rotatable member 91 in the groove 92 and is secured thereto. A second flexible member, such as a chain or cord 94, is located in the groove 93 and is likewise wound about the rotatable member and secured thereto. This cord 94 30 carries a weight 95 at its lower end. The cord 94 is so wound on the rotatable member as to tend to rotate said member in a direction to wind up the cord 41. This rotatable member 91 is freely mounted on a short shaft 96 and is 35 held thereon by a threaded nut 97. This shaft 96 is in the form of a stub-shaft threaded into the bracket 50. Mounted on this stub shaft and freely turning thereon is a lever 98. Said lever 98 is connected by means of a flexible 40 connection, such as a chain or cord 99, with an arm 100. This arm 100 is rigidly secured to a shaft 101 journaled in suitable bearings carried by the supporting base and at its forward end said shaft 101 carries a second arm 45 102 provided with a foot treadle 103, through which the shaft 101 may be oscillated and thus impart an oscillation to the lever 98. Said lever 98 on one face thereof, is provided with beveled teeth 104 which are adapted to cooperate with beveled teeth 105 formed integral with or rigidly secured to the rotatable member 91. Fixed on the shaft 96 is a collar 106 50 which has formed therein a recess 107 with one wall thereof tapered. The lever 98 has 55 a tapered dog 108 which is adapted to cooperate with a tapered wall in the recess 107. As viewed in Fig. 3, it will be noted that when the lever 98 is depressed this tapered dog moving out of the recess will move the lever 60 laterally until the beveled teeth thereon engage with the beveled teeth on the rotatable member 91. This positively connects the lever with the rotatable member so that any further depressing of the lever will turn the rotatable member. When the lever is released, it is moved in an opposite direction by means of a spring 109 which also causes the beveled teeth to move out of engagement with the beveled teeth in the rotatable member 91, so that the lever is normally out of engagement with this rotatable member.

65 When the sewing head is raised the cord 41 will turn the rotatable member, lifting the weight 95, and, therefore, the weight will always hold the cord 41 taut. If the sewing head is lowered which would tend to give slack to the cord 41, the weight will rotate the member 91 and wind up the slack and again maintain the cord 41 taut so that whatever may be the position of the sewing head this weight and rotatable member will compensate for said position. That is, it will automatically take up the cord 41 and all slack out of the same. When the treadle is depressed, therefore, and the lever is connected up with the rotatable part it will move said rotatable part in such direction as to further wind up the cord 41 and oscillate the controlling lever which will start the sewing mechanism.

70 From the above, it will be apparent that there has been provided a filled bag sewing mechanism very light in construction and which can be very cheaply made. Said filled bag sewing mechanism also includes a carriage which may carry the weight of the bag to be closed and which carriage can be moved by the operator to feed the bag to the sewing head. When the carriage reaches the end of its travel, the bag engages the rod and falling over the rod kicks the carriage in the reverse direction so that it returns to normal position for placing the bag thereon. After the bag has been placed, the operator 75 depresses the treadle and starts the sewing mechanism. When the sewing is finished and the treadle is released the sewing mechanism will be disconnected from its operating motor and the brake applied to stop the sewing mechanism.

80 The machine is readily adapted for stitching bags of varying sizes. An operator can much more readily feed the mouth of the filled bag to a stitching mechanism if said stitching mechanism is within certain reasonable range of a fixed height. In other words, the operator does not want to stoop over or reach up too high in the handling of the mouth of the bag. Therefore, it is desirable that the sewing mechanism should be set within certain range of a fixed height. The range of height between a bag of the smallest size stitched and the largest bag stitched is considerably greater than the de-

120
125
130
135

sired range for shifting the sewing machine. By the apparatus described above, it will readily be noted that the carriage may be raised when the head is lowered and therefore, the apparatus is capable of being adjusted for a wide range in heights of bags without excessive adjustment of the sewing head. Then, again, it is often desirable to adjust the carriage alone without adjusting the height of the head, so that the head may be left at a desired height for stitching and all adjustments made by raising or lowering the carriage. There are also other conditions under which it is desirable to raise or lower the head without moving the carriage up and down; as, for example, in the stitching of a bag where there is a worn place in the mouth of the bag, which makes it essential to stitch that particular bag at a lower level. It will readily be seen that all adjustments may be quickly accomplished by the above apparatus. All the operator has to do is to quickly throw the collars controlling the beveled gears and the machine may be set so as to simultaneously raise and lower the carriage and the sewing head or to raise the carriage without shifting the sewing head or to raise and lower the head without shifting the carriage. In whatever position the sewing head may be shifted the controlling mechanism operated by the treadle adapts itself for the new position of the sewing head.

It is obvious that minor changes in the details of construction and the arrangement of the parts may be made without departing from the spirit of the invention as set forth in the appended claims.

Having thus described the invention, what we claim as new and desire to secure by Letters Patent, is:

1. A filled bag closing machine including a sewing head, a support for the filled bag, and means for simultaneously adjusting said head and support vertically toward and from each other and for adjusting said head vertically independently of the support.

2. A filled bag closing machine including a sewing head, a support for the filled bag, and means for simultaneously adjusting said head and support vertically toward and from each other and for independently vertically adjusting said support.

3. A filled bag closing machine including a sewing head, a support for the filled bag, and means for simultaneously adjusting said head and support vertically toward and from each other and for adjusting said head and support vertically each independent of the other.

4. A filled bag closing machine including a sewing head, a movable support for the filled bag, and means for simultaneously adjusting said head and support vertically toward and from each other and for adjusting said head vertically independently of the support.

5. A filled bag closing machine including a sewing head, a movable support for the filled bag, and means for simultaneously adjusting said head and support vertically toward and from each other and for adjusting said support vertically independently of the head.

6. A filled bag closing machine including a supporting base, a central column rising therefrom, a sewing head adapted to slide vertically on said column, a support for the filled bag beneath the sewing head and adapted to slide vertically on said column, and means for simultaneously moving the sewing head and support toward and from each other, and for moving said head and support independently each of the other.

7. A filled bag closing machine including a supporting base, a central column rising therefrom, a sleeve vertically adjustable on the exterior of said column, a sewing head mounted on said sleeve, a motor mounted on said sleeve and adjustable with the sewing head, a support for a filled bag disposed beneath the sewing head and mounted on said column, and means for raising and lowering the sleeve.

8. A filled bag closing machine including a supporting base, a central column rising therefrom, a sleeve vertically adjustable on the exterior of said column, a sewing head mounted on said sleeve, a motor mounted on said sleeve and adjustable with the sewing head, a support for a filled bag disposed beneath the sewing head and mounted on said column, means for raising and lowering the sleeve, and a treadle controlled means for controlling the sewing mechanism of the sewing head.

9. A filled bag closing machine including a supporting base, a central column rising therefrom, a sleeve vertically adjustable on said column, a sewing head carried by said sleeve, a motor mounted on the sleeve and adjustable with the sewing head, means for raising and lowering the sleeve carrying the motor and sewing head, a treadle operated means for controlling the sewing mechanism of the sewing head, said treadle operated means including a clutch connected to a treadle and devices for automatically compensating for the different positions of the sewing head.

10. A filled bag closing machine including a supporting base, a central column rising therefrom, a sleeve vertically adjustable on said column, a sewing head carried by said sleeve, a motor mounted on the sleeve and adjustable with the sewing head, means for raising and lowering the sleeve carrying the motor and sewing head, a treadle operated means for controlling the sewing mechanism of the sewing head, said treadle operated means including a flexible member, and means for taking up the said flexible member

for giving slack thereto as the sewing head is adjusted vertically for automatically compensating for the different adjusted positions of the sewing head.

5 11. A filled bag closing machine including a support, a sewing head adjustably mounted on said support, a filled bag support beneath the sewing head, means whereby the sewing head is adjusted vertically on the support, treadle operated means for controlling the sewing mechanism of the sewing head, said treadle operated means including a clutch connected to a treadle and devices for automatically compensating for the vertical adjustment of the sewing head.

10 12. A filled bag closing machine including a support, a sewing head adjustable vertically on said support, a filled bag support beneath the sewing head, a controlling lever for controlling the stitching mechanism of the sewing head, a treadle, a rotatable member having a flexible connection with said controlling lever, means for rotating said rotatable member to take up or give slack to said flexible member as said sewing head is adjusted vertically, and devices actuated by the treadle for rotating said rotatable member to actuate the controlling lever.

15 13. A filled bag closing machine including a support, a sewing head adjustable vertically on said support, a filled bag support beneath the sewing head, a controlling lever for controlling the stitching mechanism of the sewing head, a treadle, a rotatable member having a flexible connection with said controlling lever, means for rotating said rotatable member to take up or give slack to said flexible member as said sewing head is adjusted vertically, a lever actuated by said treadle, and normally out of engagement with said rotatable member, and means for moving the lever into engagement with the rotatable member for rotating the same to actuate the controlling lever for the sewing mechanism.

20 14. A filled bag closing machine including a support, a sewing head adjustable vertically on said support, a field bag support beneath the sewing head, a controlling lever for controlling the stitching mechanism of the sewing head, a treadle, a rotatable member having a flexible connection with said controlling lever, means for rotating said rotatable member to take up or give slack to said flexible member as said sewing head is adjusted vertically, a lever adapted to be actuated by said treadle, said lever having a ratchet face, said rotatable member having a ratchet face opposed to the ratchet face of the lever, a spring for normally holding the lever disconnected from the rotatable member, and means for moving the lever laterally as it is oscillated by the treadle to cause said lever to engage the rotatable member and turn the same for actuating the controlling lever of the sewing mechanism.

25 15. A filled bag closing machine including a support, a sewing head mounted for vertical adjustment on said support, a bracket adjustably mounted on said support beneath the sewing head, spaced tracks carried by said bracket, a carriage mounted on said tracks and movable back and forth thereon, and means for simultaneously raising and lowering the sewing head and the bracket carrying the tracks.

30 16. A filled bag closing machine including a support, a sewing head mounted for vertical adjustment on said support, a bracket adjustably mounted on said support beneath the sewing head, spaced tracks carried by said bracket, a carriage mounted on said tracks and movable back and forth thereon, means for simultaneously raising and lowering the sewing head and the bracket carrying the tracks, and for adjusting the sewing head and bracket independently each of the other.

35 17. A filled bag closing machine including a supporting base, a column rising therefrom, a sleeve mounted for vertical adjustment on the exterior of said column, a sewing head mounted on said sleeve at one side of the column, a motor for operating the sewing head mounted on said sleeve on the other side of the column, a support for the filled bag located beneath the sewing head, and means for vertically adjusting said sleeve carrying the sewing head.

40 18. A filled bag closing machine including a supporting base, a column rising therefrom, a sleeve mounted for vertical adjustment on said column, a sewing head mounted on said sleeve at one side of the column, a motor for operating the sewing head mounted on said sleeve on the other side of the column, a bracket adjustable on said column, a carriage for the filled bag supported by said bracket, and means for simultaneously adjusting the sleeve carrying the sewing head and said bracket toward and from each other and for adjusting the sewing head and bracket independently each of the other.

45 19. A filled bag closing machine including a supporting base, a column rising therefrom, a sleeve mounted for vertical adjustment on said column, a sewing head mounted on said sleeve at one side of the column, a motor for operating the sewing head mounted on said sleeve on the other side of the column, a support for the filled bag, a threaded shaft for adjusting and supporting the sleeve carrying the sewing head, and a central bracket mounted on the column for supporting the lower end of said threaded shaft.

50 20. A filled bag closing machine including a supporting base, a column rising therefrom, a sleeve mounted for vertical adjustment on said column, a sewing head mounted on said sleeve on one side of the column, a motor for operating the sewing head mounted on said

- 10 sleeve on the other side of the column, a support for the filled bag, a threaded shaft for adjusting and supporting the sleeve carrying the sewing head, a central bracket mounted on the column for supporting the lower end of said threaded shaft, a hand operated shaft journaled in said central bracket, and a beveled gear carried thereby meshing with the beveled gear on the threaded shaft.
- 15 21. A filled bag closing machine including a supporting base, a column rising therefrom, a sleeve mounted for vertical adjustment on said column, a sewing head mounted on said sleeve at one side of the column, a motor for operating the sewing head mounted on said sleeve on the other side of the column, a sleeve bracket mounted for vertical adjustment on the column, tracks carried thereby, a central bracket fixed to the column, a threaded shaft supported by said central bracket for adjusting and supporting the sleeve carrying the sewing head, an independent threaded shaft mounted in the central bracket for adjusting and supporting the sleeve bracket carrying the tracks, and means whereby said threaded shafts may be simultaneously operated or independently operated.
- 20 22. A filled bag closing machine including a supporting base, a column rising therefrom, a sleeve mounted for vertical adjustment on said column, a sewing head mounted on said sleeve at one side of the column, a motor for operating the sewing head mounted on said sleeve on the other side of the column, a sleeve bracket mounted for vertical adjustment on the column, tracks carried thereby, a central bracket fixed to the column, a threaded shaft supported by said central bracket for adjusting and supporting the sleeve carrying the sewing head, an independent threaded shaft mounted in the central bracket for adjusting and supporting the sleeve bracket carrying the tracks, a hand operated shaft journaled in said central bracket, a beveled gear carried thereby, a beveled gear splined on each threaded shaft and slidable thereon, and means whereby said beveled gears on the threaded shafts may be independently placed in mesh with the beveled gear on the hand operated shaft.
- 25 23. A filled bag closing machine including a support, a sewing head carried by said support, tracks mounted on the support, and located substantially horizontally, a carriage mounted to move back and forth on the tracks, a stop for holding the carriage in normal position for receiving the bag, said stop including means whereby when said bag is placed on the carriage the stop is released.
- 30 24. A filled bag closing machine including a support, tracks mounted on the support, a carriage movable back and forth on the tracks, a sewing head overhanging the carriage, a bar supported by the tracks at the end thereof, said carriage being adapted so as to move underneath the bar, whereby the filled bag carried by the carriage will strike the bar and turn over the bar and thus be discharged from the carriage.
- 35 25. A filled bag closing machine including a support, tracks mounted on the support, a carriage movable back and forth on the tracks, a sewing head overhanging the carriage, a bar supported by the tracks at the end thereof, said carriage being adapted so as to move underneath the bar whereby the filled bag carried by the carriage will strike the bar and turn over the bar and thus be discharged from the carriage, a stop carried by the carriage for stopping the same and holding the carriage in normal position for receiving the bag.
- 40 26. A filled bag closing machine including a sewing head, a support for the filled bag and means for simultaneously adjusting said head and support vertically toward and from each other, and for adjusting said head and support vertically, each independent of the other, said means including a manually operated element, and devices whereby said element may be connected to said head, or to said support, or to both, for moving the same vertically.
- 45 In testimony whereof we affix our signatures.
